UNITED STATES PATENT OFFICE.

LOUIS DUQUESNOY, OF HIAWATHA, UTAH.

VALVE-SPRING LIFTER.

1,192,286.

Specification of Letters Patent. Patented July 25, 1916.

Application filed March 15, 1916. Serial No. 84,385.

To all whom it may concern:

Be it known that I, Louis Duquesnoy, a citizen of the United States, residing at Hiawatha, in the county of Carbon and State of Utah, have invented new and useful Improvements in Valve-Spring Lifters, of which the following is a specification.

This invention relates to certain novel and useful improvements in valve spring lifters for lifting the valve springs of internal combustion engines so that the valves may be relieved of the influence of the spring and removed from the engine conveniently and quickly.

In carrying out the present invention, it is my purpose to improve and simplify the general construction of valve spring lifters and to provide a valve spring lifter which may be conveniently and quickly put into service and which may be operated to lift the valve spring with a minimum effort on the part of the operator.

It is also my purpose to provide a device of the class described which will embrace the desired features of simplicity, efficiency and durability, and which may be stored in a small space so that the lifter may be carried about in a tool kit or tool box.

With the above and other objects in view, the invention consists in the construction, combination and arrangement of parts hereinafter set forth in and falling within the scope of the claim.

In the accompanying drawings; Figure 1 is a view in side elevation of a valve lifter constructed in accordance with my present invention, the same being shown in use, a portion of an engine being illustrated conventionally. Fig. 2 is a top plan view of the head of the lifter. Fig. 3 is a plan view of the operating lever. Fig. 4 is a view in side elevation of the same. Fig. 5 is a cross sectional view through one end of the operating lever. Fig. 6 is an enlarged side elevation of the head shown in Fig. 2.

My improved valve lifter is particularly adapted for use in connection with motors having removable heads that are designed to be taken off of the cylinders in order that access may be had to the valve, such, for instance, as a Ford motor. In this type of motor, the head is usually secured in position on the cylinders by means of bolts passed through alining openings in the head

piece and the cylinder casting and these openings are as a rule, arranged between the valves of the respective cylinders.

Referring now to the drawings in detail, 1 designates a head piece formed with laterally projecting wings 2, 2 adapted to overlap the valve heads and engage such heads. Formed in the head piece 1 and adapted to aline with the bolt holes between the valve heads is an opening and threaded through such opening and into the alining opening in the cylinder is a bolt 3 having the upper end thereof equipped with wings 4 whereby the bolt may be rotated. Immediately below the wings 4, the bolt 3 is preferably provided with a lock nut 5 whereby the bolt may be locked in position to hold the head piece in proper place. The outer end of the head piece, that is, the end remote from the valve heads, projects beyond the side wall of the engine and is formed with a downwardly projecting arm 6 having the lower end provided with a hook 7.

8 designates an operating lever having one end portion rounded to form a handle 9, the other end forked as at 10 to receive the valve stem, and the central portion formed with a cross-shaped slot 11. The lower side of the lever 9 contiguous to the transverse portions of the slot 11 is formed with grooves 12, while the upper surface of the forked end of the lever, contiguous to the fork, is formed with a depression 13.

14 designates a chain of suitable length of elongated links, as clearly illustrated in Fig. 1 of the drawings.

In practice, the head piece of the cylinders of the engine is removed and the head piece 1 secured in position to engage the wings 2 with the heads of the valves of one of the cylinders, the bolts 3 holding the head piece 1 in proper position. One end of the chain 14 is now engaged with the hook 17 and the other end of the chain passed through the cross shaped slot 11. The forked end 10 of the lever is now slipped beneath the lower end of the valve spring, around the stem of the valve, and the lower end of the spring engages in the depression 13. The chain is now turned so that the upper end of the link immediately below the slot 11 engages in the grooves 12, thereby forming a fulcrum for the lever 8 so that the latter may be swung to compress the spring and thereby

release the valve whereby the pin at the lower end of the valve stem may be removed and the valve withdrawn from the cylinder.

While I have herein shown and described the preferred form of my invention by way of illustration, I wish it to be understood that I do not limit or confine myself to the precise details of construction herein described and delineated, as modification and variation may be made within the scope of the claim and without departing from the spirit of the invention.

I claim:

In a valve spring lifter of the class described, a head piece adapted to be secured to the upper end of the cylinder, an arm formed on said head piece and depending therefrom, an operating lever having a

forked end adapted to engage beneath the valve spring, and a handle end, and formed centrally with a cross-shaped slot, a chain having one end adapted to be secured to said arm and the other end adapted to be passed through said cross-shaped slot in said lever, the link of said chain immediately below said slot engaging the lever to form a fulcrum, and wings formed integral with said head piece and overlapping the valve heads.

In testimony whereof I affix my signature in presence of two witnesses.

LOUIS DUQUESNOY.
